UNITED STATES PATENT OFFICE

2,155,065

COLLAR SUPPORT

James W. Steele, Kansas City, Mo.

Application March 20, 1937, Serial No. 132,036

5 Claims. (Cl. 223—83)

The present invention relates to collar supports for use by laundries as a temporary means for reinforcing the collars of shirts, and aims to provide an improved device of this type for preserving the proper contour of the collars from the time they are laundered until they are delivered to the customer.

Accordingly, it is an object of the invention to provide an efficient and economical device for supporting or reinforcing the collar by means embracing either or both faces of the neckband of the collar and having means for holding the device in place by engagement with either or both the button and buttonhole of the neckband.

One economical form of the invention comprises a support having portions for appropriately reinforcing engagement with either or both faces of the collar neckband, and suitable tongues projecting from one of said reinforcing portions for retaining engagement with the button and buttonhole of the neckband.

With the foregoing general objects in view, the invention will now be described by reference to the accompanying drawing illustrating a suitable form of embodiment of the proposed improvements, after which those features and combinations deemed to be novel will be particularly set forth and claimed.

In the drawing—

Figure 1 is a perspective view of the collar portion of a shirt fitted with a collar support constructed in accordance with the present invention;

Figure 2 is a perspective view of the improved collar supporting device;

Figure 3 is a plan view of a blank stamped as required for producing the improved collar support; and

Figure 4 is a fragmentary perspective view similar to Figure 1 but with portions broken away to show the relation of one of the retaining elements to the button of the shirt neckband or collar.

Referring now to the drawing in detail, the improved device is illustrated as constructed from suitable flexible material, such as a fair grade of cardboard, which is appropriately stamped to produce collar neckband engaging portions 5, 6, for engagement with the outer and inner faces, respectively, of a collar neckband 7, the cuts or slit 8 dividing said portions 5 and 6 being interrupted to leave a flexible connection 9 at a suitable point corresponding to the meeting ends 55 of the collar 10. This double collar support con-

struction is substantially that set forth in my Patent No. 1,879,918 of September 27, 1932.

In the present construction I provide the outer portion 5 of the support with a tongue 12 which is adapted for insertion through the buttonhole 14 of the collar neckband, and also with the tongue 15 having its end suitably notched or recessed as indicated at 16 for retaining engagement with the attaching threads or shank portion of the button 17 corresponding to said buttonhole 14 (as clearly illustrated in Figure 4). Preferably, although not entirely essential to the invention, these tongues 12 and 15 are conveniently stamped from the body portion of the supporting member 5, as clearly illustrated in Figures 2 and 3.

In the use of the device, the operator at the laundry simply applies the support to the finished shirt by inserting the portion 5 between the folds of the collar 10 and against the outer face of the neckband 7, during which operation the tongue 12 is thrust through the buttonhole 14, and the tongue 15 is deflected beneath the buttonhole strip 20 and into engagement with the threads or shank portion of the button 17—25 as shown in Figure 4, after which the outer portion 6 of the support is simply turned back into the collar for bracing engagement with the inner face of the neckband 7,—all as clearly represented in Figure 1.

It will therefore be seen that I have provided a practical and efficient construction embodying desirable features of improvement over my previously patented device above referred to, and having all the collar reinforcing advantages 35 of the construction, as covered by the aforesaid patent, that is, double supporting means for bracing engagement with both the outer and inner faces of the neckband portion of the collar; besides which the improved device includes efficient retaining means for holding the device in proper position until removed by the customer. The construction is very simple and can be economically produced without requiring any extra material for including the retaining means, 40 which is merely stamped from the stock already comprising the outer reinforcing member of the device, and which stamping operation and cutting of the blank for the support are all produced in one operation.

Moreover, the device is convenient for use, and with but very little experience can be applied into its proper position by the operative as she completes the finishing operation on the garment.

While I have illustrated and described what I 55

now conceive to comprise the preferred form of support constituting the present improved construction, modifications are of course possible within the spirit and scope of the invention; as, for example, the outer member 5 with the tongues formed as a part thereof may be employed independently of the inner member 6, and said member omitted entirely with a corresponding saving of material, in cases where the laundry operator does not require the double form of the support; accordingly, I desire to be understood as reserving the right to make whatever changes or modifications may fairly fall within the scope of the appended claims.

15. What I claim is:—

1. Collar bracing and stiffening means for collar attached shirts comprising a collar supporting member embracing the inner neck-engaging face of the neckfold of the collar, a collar stiffening member for insertion between the inner and outer folds of the collar and connected with said first member at the meeting ends of the collar, said second member having a tongue extending transversely of the strip and one end of said tongue being free and projectible through a button-hole of said neckband.

2. Collar bracing and stiffening means for collar attached shirts comprising a collar supporting member embracing the inner neck-engaging face of the neckfold of the collar, a collar stiffening member for insertion between the inner and outer folds of the collar and connected with said first member at the meeting ends of the collar, said second member having a tongue formed with a notch or recess for engagement with the shank or attaching threads of a button carried by said neckband.

3. Collar bracing and stiffening means for collar attached shirts comprising a collar supporting member embracing the inner neck-engaging

face of the neck-fold of the collar, a collar stiffening member for insertion between the inner and outer folds of the collar and connected with said first member at the meeting ends of the collar, said second member being provided with a pair of tongues, one extending transversely of said stiffening member and projecting through a button-hole of the neckband and the other extending longitudinally of said stiffening member into engagement with the shank or attaching threads of a button carried by said neckband.

4. A collar supporting device comprising an elongated strip of flexible material insertable into position for embracing a substantial portion of the neckband of a collar with the upper and lower edges of said strip conforming approximately to the upper and lower margins respectively of said neckband, a portion of the material of said strip between its upper and lower edges forming a pair of tongues, one extending transversely of said strip and projecting through a buttonhole of said neckband and the other extending longitudinally of said strip into engagement with the shank or attaching threads of a button carried by said neckband.

5. A collar supporting device comprising an elongated strip of flexible material insertable into position for embracing a substantial portion of the neckband of a collar with the upper and lower edges of said strip conforming approximately to the upper and lower margins respectively of said neckband, the material of said strip between its upper and lower edges being cut with merging slits forming a pair of tongues, one extending transversely of said strip and projecting through a buttonhole of said neckband and the other extending longitudinally of said strip into engagement with the shank or attaching threads of a button carried by said neckband.

JAMES W. STEELE.
